UNITED STATES PATENT OFFICE.

JOHN F. WALKUP, OF EMPORIA, KANSAS.

CHARGE CONTROL FOR INTERNAL-COMBUSTION ENGINES.

1,294,000.

Specification of Letters Patent. Patented Feb. 11, 1919.

Application filed April 14, 1916. Serial No. 91,139.

To all whom it may concern:

Be it known that I, JOHN F. WALKUP, a citizen of the United States, residing at Emporia, in the county of Lyon and State 5 of Kansas, have invented certain new and useful Improvements in Charge Controls for Internal-Combustion Engines, of which the following is a specification.

This invention relates to an improvement 10 in charge controls for internal combustion engines, and more particularly to such a control as is adapted for use with kerosene, gas, or oil engines of the four-stroke-cycle type.

15 An object of my invention is to provide a control means for explosive engines which may be manually set to vary the proportionate parts of each of the ingredients of the mixture, and which will when the engine 20 is in operation act automatically to control the entire volume of the mixture as supplied to the engine.

A further object lies in the provision of 25 means by which the normal setting of the main charge supply control can be varied, and also means by which the maximum decrease of the supply will be accomplished at any desired speed of operation of the engine.

30 With the above and other objects in view, my invention consists in certain novel features of construction and combination of parts which will be hereinafter set forth in connection with the drawings and then more 35 particularly pointed out in the claim.

In the drawings:

Figure 1 is a transverse sectional view 40 through an engine cylinder and through the intake and exhaust ports thereof with my invention illustrated in an operative relation.

Fig. 2 is an enlarged detail sectional view to better show the construction of the mixing device.

45 Fig. 3 is an enlarged detail view showing the throttle valve control governor means.

Fig. 4 is a detail view showing the manner of connecting the throttle valve shifting 50 rod to the governor structure.

Fig. 5 is a fragmentary detail view showing the connecting arms to the throttle valve.

As is shown in Fig. 1, the cylinder 1 is 55 illustrated as being of the valve-in-head type, and the intake chamber 2 and the ex-

haust chamber 3 are placed in such relation that the intake and exhaust valves 4 and 5 are located adjacent, the partition wall 6 separating the chambers 2 and 3. The intake passage 7 is extended from the chamber 2 through the side of the cylinder 1, and the exhaust passage 8 is extended in line with the passage 7 preferably through the opposite side of the cylinder 1.

The tappet rods 9 and 10 are mounted to be capable of endwise sliding movement through suitable bearing openings provided in the cylinder casing and are extended in line with the stems 11 and 12 of the intake 70 and exhaust valves 4 and 5, which stems are screw-threaded at their ends and are screwed into mating orifices provided on the ends of the tappet rods 9 and 10. Coil springs 13 and 14 are mounted around the 75 tappet rods 9 and 10 to normally exert tension to close the valves 4 and 5 against their seats, and a cam shaft 15 is mounted in suitable bearings formed on the cylinder casing or upon other parts of the structure, and has the valve operating cams 16 and 17 secured thereon to engage with the bearing ends of the tappet rods 9 and 10. Where the engine is of the four-cycle type, the cams 16 and 17 will be placed so that their extreme rise will be substantially 90° apart or on the quarter turn, it being so timed that the cam 17 will first become operative, and a driving connection is established to moving parts of the engine through the gear wheel 18, the gearing for the drive to the cam shaft 15 being so proportioned that its turning movement will be timed one to two with respect to the rotation of the crank shaft of the engine.

The outer end of the intake passage is closed and a charge mixing chamber is provided at 19, below this closed outer end of the passage 7.

A water pipe 20 is led from the water-jacketed motor cylinder 1 and is connected by a union coupling 21, with a water supply nipple 22 which is passed through the side wall of the mixing chamber 19 and has the valve seat 23 formed around the inner open end thereof. A water supply control valve 24 has the screw-threaded stem 25 thereof threaded to a screw-threaded orifice provided through the side wall of the mixing chamber 19 in alignment with the mounting of the water supply nipple 22 so that as this valve 24, which is of the needle type,

is turned to be threaded through the screw-threaded orifice of the case of the mixing chamber 19, it will be brought to bear in the valve seat 33 or its proximity with respect to the seat will be varied to vary the supply of water through the nipple 22. A suitable index and restraining finger 26 is mounted on the case of the mixing chamber to work against the milled edge of the hand-wheel 27 by which the valve 24 is manipulated and by placing designating markings on this hand-wheel, settings may be made with respect to the pointer or finger 26 to open or close the valve for the desired degree to accomplish the desired supply of water through the nipple 22. The casing portion 28 in which the mixing chamber 19 is located, has the lower end thereof internally screw-threaded and a plug-like partition 29 is screwed into this screw-threaded portion to be disposed above the lower edge of the casing 28, and is provided with a central fuel passage 30 establishing communication from the fuel chamber 31 to the mixing chamber 19 and set against the backflow of liquid from the mixing chamber through the medium of the valve 31 which normally seats to close the passage 30 against backflow. A cap 33 is fitted over the outer end of the case 28 and has the gasoline supply pipe 34 and the kerosene supply pipe 35 passed through orifices therein to bring each of these pipes into communication with the fuel chamber 31.

A mixture supply nipple 36 is secured through a screw-threaded orifice 37 in the wall of the intake passage 7 which nipple establishes communication to the mixing chamber 19, and a locking and packing nut 38 is fitted over this nipple to bear down against the inner wall of the passage 7 to establish a fluid-tight connection. The intake nipple 36 has a valve seat 39 formed at the inner end of the passage provided therethrough, and a valve stem 40 is screw-threaded to be received through the screw-threaded orifice 41 in the opposite wall of the passage 7 so that the end of this stem 40 which is of the needle valve type, will fit within the valve seat 39. A hand-wheel 42 is provided on the outer end of the stem 40 and an index and holding finger 43 is mounted to engage with and have bearing against the milled edge of the hand-wheel 42 to retain the manual settings thereof.

A hot air pipe 44 is passed through the closed end of the intake passage 7 and is so located that the heated air passing therethrough will flow around the open end of the nipple 36 to give the necessary heat to maintain the kerosene or heavier oil in the volatile form and to preclude the possibility of condensation thereof through cooling. An auxiliary air supply opening 45

is provided through the closed end of the passage 7 and a manually operable valve 46 is provided to permit control of the supply of atmospheric air through this passage 45, it being preferable that a check valve 47 be provided to check this passage 45 against the outflow of the mixture as contained in the intake passage 7.

A shaft 48 is mounted across the intake passage 7 and a butterfly throttle valve 49 is mounted on this shaft in such relation that as the shaft 48 is turned, movement will be given to the throttle valve to increase and decrease the size of the passage and thus to control the flow of fluid from the head end of the intake passage 7.

It is preferable that the shaft 48 be loosely mounted in its bearing and a cranked operating arm 50 is connected with one end of the shaft to permit turning of the same to accomplish the desired setting of the throttle valve 49 in its various angular dispositions across the intake passage 7.

A bearing bracket 51 is mounted on the engine structure at a point adjacent to the free end of the cam shaft 15, and a bearing 52 is provided in line with the bearing 51 in such relation that the governor shaft 53 is mounted revolvably in these bearings 52 to extend at right angles to the cam shaft 15. A large miter gear 54 is keyed or otherwise secured on the end of the cam shaft 15 and a small miter or bevel gear 55 is secured on the contiguous end of the governor shaft 53 to mesh with the bevel or miter gear 54 and to transmit movement to the governor shaft 53 at an increase in speed as the cam shaft 15 is revolved.

The upper end of the governor shaft 53 is provided with external screw-threads as shown at 56, and the head 57 is rigidly secured on the extreme upper end of the shaft 53. A sliding base 58 is mounted on the shaft 53 to normally rest through its own gravity weight down against the bearing 52, suitable ball bearings being provided to relieve friction between the parts when the shaft 53 is turned, and this sliding base structure 58 has the yoke 59 formed on each side of the shaft at the upper end of the base member, and these yokes are each provided with the central bearing opening.

Toggle arms 60 and 61 are pivotally connected with the fixed head 57 and toggle arms 62 and 63 are connected with the yokes 59 and are extended up to be connected at their free ends with the free ends of the toggle links or arms 60 and 61, and the weights 64 and 65 are secured on the pins 66 by which the upper and lower toggle links or bars are pivotally connected together, the parts being thus so arranged that as the governor shaft 53 is rotated, the portions carrying the governor weights 64 and 65 will be given the

same rotation due to the fact that the head 57 is fixed on the upper end of the governor shaft 53, the parts being thus so arranged that due to centrifugal action, the governor 5 weights 64 and 65 will exert an outward drawing action against the various toggle members and in consequence, the sliding base structure 58 is raised along the governor shaft 53. As has been stated, the upper end 10 of the governor shaft 53 is provided with the external screw-threads and an adjusting nut 67 having the external surface thereof knurled to permit ready manual turning of the same is fitted on the screw-threaded portion to be adjustable along the length of the upper portion of the shaft 53. The arms 68 are extended upwardly from yokes 59, and a collar 69 is carried by the upper ends of these arms 58 to be loosely received around 15 the screw-threaded portions of the shaft 53, and thus as the weights 64 and 65 are carried outwardly through the centrifugal action due to the turning of the shaft, the sliding base 58 will be raised, but at the same time 20 the height to which the same is to be raised in its extreme movement may be regulated by setting of the nut 67 so that the collar 69 will bear thereagainst when the base 58 has been raised to the proper degree of movement.

A collar 70 is mounted around the sliding base 58 and a sleeve 71 is extended downwardly from one side of this collar 70, this sleeve having the internal screw-threads as shown at 72 formed in the bore thereof. It is the intention that the sliding base structure 58 shall turn with the governor shaft 53 and the collar 70 must remain stationary, in view of which it is preferable that the ball 35 bearings 73 be mounted between the base structure 58 and the collar 70 to relieve the friction incident to the turning of the base structure, and also this ring 70 is received in a substantially groove-shaped formation 40 on the base 58 so that as the base has sliding movement either up or down, the ring or collar 70 is positively moved therewith. A valve operating rod 74 is provided at its upper end with the external screw-threads 45 adapted to mesh with the screw-threads 72 of the sleeve 71, and to thus permit this rod to be adjustably mounted in conjunction with the collar 70, and at its lower end this rod 74 has an orifice adapted to receive the pin 75 mounted on the outer end of the throttle 50 valve operating arm 50. By removing the rod 74 from its fitting over the pin 75, this rod may be turned to secure the proper adjustment into or out of the screw-threaded orifice of the sleeve 71, and then the locking 55 nut 76 may be tightened in place and the rod 74 may be again fitted over the pin 75 so that

as the collar 70 is moved through the movement of the sliding base structure 58 generated by the centrifugal swinging out action 60 of the governor weights 64 and 65; the valve operating lever 50 will be swung around the body of the shaft 48 and the throttle valve 49 will be actuated. A spring 77 is connected between the pivot pins 66, by which the 65 upper and lower toggle bars or arms are pivotally connected together and in this way, the weights 64 and 65 are normally held 70 swung to relations closely adjacent the shaft 53 and the weights 64 and 65 will not be permitted to immediately raise the base structure 58 to its extreme upward position when 75 turning movement of the governor shaft 53 is initiated.

From the foregoing it will be seen that 80 I have provided a structure in which manual adjustment of the parts may be made to obtain the desired proportionate parts of the various ingredients in the explosive mixture and also the proportion of mixture supplied 85 to the air volume passing through the intake passage to the motor cylinder, and further that parts of the mechanism may be checked so that the entire volume of air and explosive mixture passing to the intake chamber 90 2 will be varied in accordance with the speed of rotation at which the engine is working.

While I have herein shown and described only one specific form of my invention, it 95 will be understood that various modifications might be resorted to in the form and arrangement of the several parts without departing from the spirit and scope of my invention, and hence I do not wish to be limited 100 to the exact disclosure but only to such points as may be set forth in the claim.

I claim:

In a charge control for internal combustion engines, the combination with an intake 105 opening into the engine cylinder, a throttle valve therein, a governor, and connections between the governor and valve; of a hot-air supply passage to the outer end of the intake, a cold air supply passage also thereto, a valve 110 for controlling the cold air passage, a mixing chamber contiguous to the intake and opening to the same between said air passages and the throttle valve, means for manually controlling the opening, and valved means for 115 supplying the fluid fuel to said mixing chamber.

In testimony whereof I affix my signature in presence of two witnesses.

JOHN F. WALKUP.
